TRUSTEE, OF HARTFORD, CONNECTICUT.

VALVE MECHANISM.

1,157,972.

Specification of Letters Patent.

Patented Oct. 26, 1915.

Application filed January 28, 1915. Serial No. 4,921.

To all whom it may concern:

Be it known that I, HOLDEN P. BALLOU, a subject of the King of Great Britain, and residing at Hartford, in the county of Hartford and State of Connecticut, have invented certain new and useful Improvements in Valve Mechanism, of which the following is a specification.

This invention relates to valve-mechanism.

Valve mechanism involving my invention is of especial utility when incorporated in or forming part of a pneumatic piano-player, being of such character as to secure accurate tone effects in a simple effective manner and at the same time insure precise movement of a valve or valves.

In the drawings accompanying and forming part of the present specification I have shown in detail one of the several convenient forms of embodiment of the invention which to enable those skilled in the art to practice the same will be set forth fully in the following description. I do not restrict myself to this disclosure; I may depart therefrom in several respects within the scope of the invention defined by the claims following said description.

Referring to said drawings: Figure 1 is a cross section of a vacuum chest in which are incorporated valve mechanisms constructed in accordance with the invention, the ducts shown therein being partly in elevation. Fig. 2 is a perspective view of a valve casting, and, Fig. 3 is a like view of a valve seat.

Like characters refer to like parts throughout the several views.

As intimated I provide an organization wherein a valve or valves can be guided properly in the various movements thereof, while at the same time I can insure precise regulation of one or more of such valves. By such regulation I obtain positively correct tones in playing; that is to say the player attachment can be put into exact harmony with the piano action.

In Fig. 1 of the drawings I have shown a valve or vacuum chest or box 2 such as is more fully illustrated in my contemporaneously pending application filed May 9, 1914, Serial No. 837,419. I show this chest merely to bring out the advantages of the improved structure; any other or some equivalent part might be substituted for the chest or box represented, the invention not residing in

the chest or analogous element *per se*. Fitted into the vacuum chest 2 are ducts 3 and 4 connected with pneumatics as 5, only one of the upper pneumatics being shown. The upper ends of these ducts 3 and 4 connect with vertical passages as 6 in the vacuum chest 2, the lower ends of the passages 6 opening into the vacuum chamber 7, while the upper ends of said passages are adapted to communicate with the atmosphere by way of one or more ports in valve seats as will hereinafter appear. With the vacuum chamber 7 there is connected in practice a suitable exhaust device. (Not shown). The upper ends of the passages 6 open into chambers 8 in which lower and upper valves as 9 and 10 are disposed. As will be understood the passages 6 do not connect directly with the atmosphere but do so through the intermediate chambers 8, the chamber on the left being longer than that on the right. The pairs of valves 9 and 10 are properly spaced from each other and are fastened to stems as 11 connected at their lower ends with diaphragms 12 covering the chambers 13 connected by passages as 14 through the medium of suitable ducts with a tracker board, neither the ducts nor the tracker board being shown. The bleed openings 15 extend from the main vacuum chamber 7 to the passages 14, so that when the music sheet covers the perforations in the tracker board the suction in the main chamber 7 by way of the bleed openings 15, passages 14 and chambers 13 will draw the diaphragms 12 downward to cause the valves 9 to close or seat against the upper ends of the passages 6 as shown in Fig. 1 which is the normal relation. When the vacuum in a chamber 13 is broken by communication with the atmosphere through a perforation in the tracker, the diaphragm 12 over said chamber is elevated by suction, thereby raising or opening the coacting lower valve 9 and at the same time elevating the complementary valve 10 or closing the latter against its seat as will hereinafter appear to thus put a duct as 3 or 4 into communication with the vacuum chamber 7 and result in the operation of a pneumatic as 5. The foregoing is a brief description of the vacuum chest construction and valves shown in my said application.

Preferably driven into the upper sides of the chambers 8 so as to tightly fit therein, are bushings or sleeves 16 which as shown

are of circular form. These bushings or sleeves 16 constitute suitable casings for valve seats as 17 hereinafter more particularly described. Said bushings 16 are provided on their outer sides with annular flanges 18 fitting tightly and substantially against the upper surface of the chest 2. These bushings or valve casings 16 I prefer to make of metal, sheet brass answering satisfactorily in this connection. The valve seats 17 are of cup form, being also preferably of metal, as sheet brass, their bottoms or body portions being centrally perforated as at 19 to provide bearings for and to slidely receive the respective stems 11, so that the valve seats in addition to serving as such, constitute guides for the valves. The flange or wall portions of the cup-like valve seats 17 are externally threaded to fit internal threads in the bushings or casings 16 from which, as will be inferred, said seats can be adjusted either inwardly or outwardly. The body portions of the valve seats 17 are shown perforated as at 20, there being five of such perforations (see Fig. 3) which serve a double purpose, acting as ports and also as a convenient means for receiving a spanner or other suitable tool by which said seats can be adjusted as required. By adjusting these seats, the time of closing of the valves can be regulated to thus regulate the action of the piano. When the valves become worn from use, the seats can be slightly moved inward to compensate for the wear. The valve seats are accessible and can be easily adjusted. It will be evident that when the upper valves 10 are open, they uncover the ports or openings 20 as shown in Fig. 1, so as to put the chambers 8 into communication with the atmosphere by way of said ports. When the valves 10, however, are closed, they cover the perforations or ports 20 and thereby cut off the chambers 8 from the atmosphere.

What I claim is:

- 45 1. A vacuum chest having a valve therein, a bushing fitted in said chest, a stem to which said valve is connected and a seat for the valve adjustably fitted in said bushing, the seat being perforated thereby providing a bearing to receive said stem and being also perforated to provide ports, the latter acting as means whereby the seat can be adjusted.
- 50 2. A vacuum chest having a valve therein, a bushing fitted in said chest, a stem to which the valve is connected, and a seat for the valve threaded in said bushing to permit ad-

justment of the seat, the latter being perforated thereby providing a bearing to receive the stem and being also perforated to provide ports and the latter acting as means whereby the seat can be adjusted.

3. A vacuum chest having a valve therein, a bushing driven into said chest and having an annular flange overlying the chest, a stem to which said valve is connected, and a seat for the valve threaded in said bushing for adjustment and being perforated to provide ports and to provide means whereby the seat can be adjusted.

4. A vacuum chest having a valve therein, a bushing fitted in said chest, a stem to which the valve is connected, and a seat for the valve adjustably fitted in said bushing, the seat being perforated thereby providing a bearing to receive said stem and being also ported.

5. A vacuum chest having a valve therein, a bushing fitted in said chest, a stem to which said valve is connected, and a cup-like seat for the valve, adjustably fitted in said bushing, the body portion of the seat being perforated thereby providing a bearing to receive said stem and being also ported.

6. A vacuum-chest having a valve therein, said valve being provided with a stem, a metal bushing driven into said chest and having a flange overlying the chest, a metal cup-like member fitted in said bushing, the cup-like member being externally threaded and the bushing being internally threaded to receive the threads of the cup-like member to provide for the adjustment of the cup-like member in the direction of the axis of the bushing, said cup-like member constituting a valve seat, the body of said cup-like member being centrally perforated thereby providing a bearing to slidely receive said stem and also having a series of other perforations surrounding the central perforation, said last mentioned perforations constituting ports governed by said valve and also presenting a means to receive a tool by which said cup-like member can be turned in said bushing.

In testimony whereof I affix my signature in presence of two witnesses.

HOLDEN P. BALLOU.
